Primary Examiner — Brandon M Rosati*Assistant Examiner* — Marissa J Cash(74) *Attorney, Agent, or Firm* — McDonnell Boehnen Hulbert & Berghoff LLP(57) **CLAIM**

The ornamental design for a wind energy kite tail, as shown and described.

DESCRIPTION

FIG. 1 is a perspective view of a wind energy kite tail;
FIG. 2 is a further perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof;
FIG. 8 is a bottom view thereof;
FIG. 9 is a front view of a first alternative configuration of use;
FIG. 10 is a left side view thereof;
FIG. 11 is a front view of a second alternative configuration of use; and
FIG. 12 is a left side view thereof.
FIG. 13 is a front view of a third alternative configuration of use;
FIG. 14 is a top view thereof;
FIG. 15 is a front view of a fourth alternative configuration of use; and,
FIG. 16 is a top view thereof.
The broken lines illustrate portions of the wind energy kite tail that form no part of the claimed design.

1 Claim, 16 Drawing Sheets(56)
